UNITED STATES PATENT OFFICE.

CLIFFORD KIRBY MACDONALD, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

NURLING-MACHINE.

1,358,169.

Specification of Letters Patent. Patented Nov. 9, 1920.

Application filed December 9, 1916. Serial No. 136,017.

To all whom it may concern:

Be it known that I, CLIFFORD K. MACDONALD, a citizen of the United States, residing at Brockton, in the county of Plymouth and State of Massachusetts, have invented certain Improvements in Nurling-Machines, of which the following description, in connection with the accompanying drawings, is a specification, like reference characters on the drawings indicating like parts in the several figures.

This invention relates to that type of machine which operates upon the soles of boots and shoes by impressing or indenting the surface of the soles around their edges, usually to obliterate the marks made by inserting fastenings and to ornament the shoe sole. This class of machines is known to the trade as "nurling" machines and as structural characteristics, includes an indenting tool, a work edge gage in fixed relation to the tool, and a work support, including a work engaging and supporting arm or horn, the end of the arm engaging the insole of the inverted shoe at the outer edge of the shoe and acting as an abutment against which the shoe is held while it is turned to present successive portions of the bottom of the outsole to the action of the indenting tool, the edge of the sole at all times being maintained in contact with the edge gage.

As previously constructed or proposed, the work engaging arm or horn has been immovable laterally relatively to the fixed edge gage so that the distance between the work edge gage and the abutment edge of the arm or horn end has been fixed. Under these conditions shoes provided with "extension" soles or with sole edges projecting beyond the sides of the shoe a greater distance than that between the edge gage and horn end, could not be properly positioned on the work support and in contact with the edge gage. A construction providing for relative lateral movement between the edge gage and work support to compensate for such differences in the width of shoe soles, is therefore a desideratum.

It is also desirable to have means for varying the normal or minimum distance between the edge gage and the end of the work sup-

porting arm, since this distance should vary to accommodate different classes of shoes. This will be readily apparent from the fact that men's, women's and children's shoes vary in the distance from the inside of the shoe at one edge to the outer edge of the adjacent sole and the linear relation between the edge gage and work support must be correspondingly varied for the minimum distance for the various classes and types of work. And in order that accurate adjustment may be secured, it is further desirable that a determinate line of lateral adjusting movement be uniformly maintained.

It is the aim of the present invention to provide a machine of the described type embodying these various desirable features.

Accordingly, one feature of the invention comprises, in combination, an indenting tool, a coöperating work edge gage and a work support positioned in coöperative relation with said gage and constructed to rotate in response to the movement by the operative of a shoe thereon, to position itself in accordance with the shape of a shoe in its different positions thereon, and to yield under pressure of supported work in a direction laterally of and away from said edge gage. The advantages of such a construction have been previously stated, the self adjusting movement of the work support in response to pressure of the work being obvious.

A further feature of the invention consists in a work engaging arm positioned in co-operative relation with a gage and supported to yield laterally relatively to and away from said gage, in a uniformly maintained direction. The line of adjusting movement will always be the same with reference to a fixed point on the gage, such for instance, as radially of a combined feed wheel and gage having a fixed axis of rotation as in the present case, and the spring opposing laterally outward movement of the work support can act uniformly to hold the edge of the shoe sole against the edge gage at all times since the movement of the work support may be confined to the direction of compression and expansion of the spring.

Another feature of the invention consists in an arm having a work engaging end in co-

operative relation with a gage and supported for movement relatively to and laterally of said gage, with means normally tending to move said arm toward said gage and adjustment means to limit said movement to adjust the normal linear relation of said gage and the work engaging end of said arm. This construction provides for the initial adjustment of the parts for the purpose and with the advantages previously recited.

The above described and other features of the invention will be more clearly apparent from the following detailed specification when read in connection with the accompanying drawings, in which—

Figure 1 is a view in side elevation of a nurling machine of the described type embodying the features of the present invention.

Fig. 2 is a fragmentary vertical section on an enlarged scale showing the connections between the work supporting arm and its supporting standard, and

Fig. 3 is a detail in perspective of part of the connecting elements.

The usual frame 2 of this type of nurling machine is formed with a head in which the power shaft is journaled and from which depends a reciprocable carrier 4 having a suitable nurling tool 5 at its lower end. Depending from the machine head and positioned in a plane slightly below the nurling tool is a power driven feed wheel 6. The work is supported by a standard 8 having suitable treadle connections 10 to lift it to operative position. This standard is guided through a bracket 12 extending laterally from the frame of the machine and, adjacent to its outer end is shouldered to provide a short reduced section 14 and a longer and further reduced section 16 terminating in a substantially spherical knob 18. Preferably, the bracket 12 carries a boss 22 having a sleeve extending through the opening in the bracket and rigidly securing the boss to the bracket. The boss is formed at its upper inner edge with a lateral offset 24 slotted to provide a lateral guiding slot 26, which extends in a direction substantially radial of the feed wheel 6.

An adjusting carrier is seated over the upper end of the standard 8 and comprises a tubular portion 28 inclosing the reduced end section 16 of the standard and having its upper end closed and formed with a substantially spherical socket 30 resting upon the spherical end 18 of the standard.

At its lower end the carrier sleeve 28 is provided with a lateral bearing face 32 and at a point below the bearing face with diametrically opposed lateral offsets 36 and 44. The interior of the sleeve 28 is of a diameter greater than the diameter of the section 16 of the standard and substantially coincident with the diameter of the section 14. This

internal diameter, however, at that portion of the sleeve in alignment with the offsets 36 and 44 is enlarged to afford substantial clearance between the adjacent inner face of the tubular portion 28 and the periphery 70 of section 14 of the standard.

The carrier is permitted to rock on the spherical end of the supporting standard, the amount of rocking motion and its direction being determinately controlled. To this end, the offset 36 is bored to receive and guide a cupped pressure member 38 whose socket receives a coiled spring 40, the outer end of which engages a tensioning nut 42 screwing into the threaded outer end of the 80 offset. The tension of the spring forces the pressure member 38 against the section 14 in the standard and tends to rock the sleeve on the spherical end of the standard to move its upper end toward the rear of the machine or in the direction of the feed wheel 6. This direction is controlled and is preferably made substantially radial to the feed wheel by means of a finger 46 depending from the lateral offset 44 and guided in the 85 slot 26 of the offset 24 of the boss. The position of the carrier member on the standard is determined and the rocking movement of the carrier on the standard may be variably and determinately limited by the position of the inner end of a screw 48 carried by the offset 44 for engagement with the section 14 of the standard at a point diametrically opposite the pressure member 38. The screw 48 may be locked in adjusted position by means of a suitable lock nut 50.

In nurling machines of this class, the inverted shoe is carried upon an arm or horn positioned to cause the engagement of the sole of the shoe with the feed wheel and mounted for rotation, the insole of the shoe resting upon a flat portion or button at the upper end of the horn which is usually substantially in alignment with the axis of rotation of the horn, the horn being turned about this axis as successive portions of the edge of the shoe are brought beneath the nurling tool. The face of the flattened upper end or button of the shoe supporting arm or horn is maintained against the insole of the shoe with the edge of the button engaging the side of the shoe as the shoe is turned both with and relatively to the horn so that successive portions of the sole edge 110 are held in contact with the feed wheel 6 by the pressure of the edge of the horn button against the inside edge of the shoe while the nurling tool is operating upon the bottom of the sole adjacent to the feed wheel and at 115 a point above the supporting upper or button end of the horn.

The distance between the periphery of the feed wheel 6 and the inner edge of the horn button which engages the edge of the shoe 130

at the inside will vary with shoes with sole edges of different widths and with upper materials of different thicknesses, and the described construction of carrier member is arranged to provide for the automatic accommodation of the position of the upper end of the shoe supporting horn to this variable distance.

A split sleeve 52 is journaled upon the carrier sleeve 28, its base having a bearing upon the bearing surface 32 of the carrier. A split bearing sleeve is preferable, since it is desirable to have such degree of friction as will resist free turning of the horn, but will permit, nevertheless, rotation of the horn about the axis of standard 8 to adapt the position of the horn to the shape of the inside of the shoe in the different positions to which it is moved by the operative. Accordingly, the sleeve may be provided with alined offset ears 54 to receive suitable clamping devices. The sleeve 52 is provided at its outer side with a laterally offset socket portion 56 in which the lower end 58 of a horn 60 is clamped, the horn curving upwardly and inwardly to position the flat button 62 at its upper end in substantial alinement with the nurling tool 5 and with the axis of the standard 8.

When an inverted shoe is mounted upon the horn 60 with the outer edge of its sole engaging the periphery of the feed wheel 6 and with the inner edge of the button 62 engaging the inside of the shoe at its outer edge, the spring 40 of the carrier member will yieldingly hold the edge of the shoe in this position. Obviously, the screw 48 is adjusted to permit the spring 38 to move the button inwardly toward the feed wheel and to a distance from the feed wheel which will represent the minimum width of the soles of shoes of the type to be operated upon. When a shoe is mounted upon the horn, as described, therefore, the spring 38 will maintain the edge of the shoe sole against the feed wheel at all times as the shoe is turned to present different successive portions of its edge to the nurling tool. With shoes having sole edges of varying widths or upper materials of varying thickness the carrier member spring will permit the button 62 of the horn to be moved radially outward from the feed wheel by the pressure of the feed wheel against the sole edge to compensate for the greater width or thickness and will move the button end of the horn radially inward toward the feed wheel for the lesser width or thickness so that the described construction affords a work support which automatically accommodates itself to the various described conditions in operating upon the shoes. The direction of lateral movement will be uniform and is determined by the fixed angu-

lar relation of the guiding slot 26 for the projection 46 to the feed wheel and edge gage 6.

Having thus described my invention what I claim as new and desire to secure by Letters Patent of the United States is:—

1. A machine of the class described having, in combination, a tool for operating upon the faces of shoe soles, a coöperating sole edge gage substantially at right angles to the plane of the operative face of the tool, and a work supporting horn formed and arranged to be capable of entering the forepart of a shoe and rotatably mounted so as to position itself in accordance with the shape and position of the inside of the part of the shoe adjacent to that portion of the edge of the sole which from time to time may be brought into coöperative relation to said gage and having means yieldingly to maintain the edge of the supported sole against said gage, said means being arranged to permit the work support to yield in a direction transversely of the tool and laterally away from the edge gage in response to pressure of the gage against the sole edge.

2. A machine of the class described having, in combination a tool for operating upon the faces of shoe soles, a coöperating sole edge gage substantially at right angles to the plane of the operative face of the tool, a work supporting arm, a standard upon which the arm is mounted movable to position the face of the supported sole in coöperative relation to the tool, and connections between said arm and standard effective yieldingly to maintain the edge of the supported sole against said gage and to permit said arm to yield in a direction transversely of the tool and laterally away from the edge gage in response to pressure of the gage against the sole edge.

3. A machine of the class described having, in combination, a tool for operating upon the faces of shoe soles, a coöperating sole edge gage substantially at right angles to the plane of the operative face of the tool, and a work support movable in response to the movement of the shoe thereon by the operative to position different parts of the face of the supported sole in coöperative relation to the tool and having means yieldingly to maintain the edge of the supported sole against said gage, said means being arranged to permit the work support to yield in a direction transversely of the tool and laterally away from the edge gage in response to pressure of the gage against the sole edge, said work support being mounted to turn about an axis to present successive portions of a sole edge to said gage and successive portions of the sole face to said tool.

4. A machine of the class described having, in combination a tool for operating upon the faces of shoe soles, a coöperating sole edge gage substantially at right angles to the plane of the operative face of the tool, a work supporting arm, a standard upon which the arm is mounted movable to position the face of the supported sole in coöperative relation to the tool, and connections between said arm and standard effective yieldingly to maintain the edge of the supported sole against said gage and to permit said arm to yield in a direction transversely of the tool and laterally away from the edge gage in response to pressure of the gage against the sole edge, said arm being mounted to turn relatively to its supporting standard about an axis to present successive portions of a sole edge to the gage and successive portions of the sole face to said tool.
5. A machine of the class described having, in combination, a tool for operating upon the faces of shoe soles, a coöperating sole edge gage substantially at right angles to the plane of the operative face of the tool, and a work support movable in response to the movement of the shoe thereon by the operative to position different parts of the face of the supported sole in coöperative relation to the tool and having means to maintain the supported sole edge against said gage constructed and arranged to permit the work support to yield in a direction transversely of the tool, and laterally away from the edge gage at a uniform angle to the engaged face of said gage in response to the pressure of the gage against the sole edge.
6. A machine of the class described having, in combination a tool for operating upon the faces of shoe soles, a coöperating sole edge gage substantially at right angles to the plane of the operative face of the tool, a work supporting arm, a standard upon which the arm is mounted movable to position the face of the supported sole in coöperative relation to the tool, and connections between said arm and standard effective yieldingly to maintain the edge of the supported sole against said gage and to permit said arm to yield in a direction transversely of the tool and laterally away from the edge gage in response to pressure of the gage against the sole edge, with means to control and uniformly to maintain the direction of said lateral movement of the arm, said arm being mounted to turn relatively to its supporting standard about an axis to present successive portions of the sole edge and face to said gage and tool, respectively.
7. A machine of the class described having, in combination, a tool for operating

upon the faces of shoe soles, a coöperating sole edge gage substantially at right angles to the plane of the operative face of the tool, a work supporting horn formed and arranged to be capable of entering the forepart of a shoe and rotatably mounted so as to position itself in accordance with the shape and position of the inside of the part of the shoe adjacent to that portion of the edge of the sole which from time to time may be brought into coöperative relation to said gage and having means normally tending to move said support toward said sole edge gage to maintain the sole edge in contact with the gage, and means adjustably to limit said movement of the work support.

8. A machine of the class described having, in combination, a tool for operating upon the faces of shoe soles, a work edge gage positioned in determinate relation to said tool, an arm having an upper end to engage the insole of an inverted shoe at the outer edge of the shoe, and constructed and arranged for rotation in response to the movement of the shoe thereon by the operative, a standard, and connections between the standard and said arm constructed and arranged normally to position the upper end of said arm in determinate coöperative relation to said edge gage including a spring to hold the sole edge of a supported shoe in contact with said edge gage and arranged to permit said arm to yield to pressure against supported work in a direction laterally of and away from said edge gage.

9. A machine of the class described having, in combination, a tool for operating upon the faces of shoe soles, a work edge gage positioned in determinate relation to said tool, an arm having an overhanging work supporting end positioned substantially in vertical alinement with said tool constructed and arranged to position itself in accordance with the position to which the shoe supported thereby may be moved by the operative and in coöperative relation to said edge gage and supported for rotation about an axis substantially in vertical alinement with said tool, and having means arranged to permit yielding movement of said arm laterally of and away from said gage through lateral pressure against work supported by said arm.

10. A machine of the class described having, in combination, a tool for operating upon the faces of shoe soles, a work edge gage positioned in determinate relation to said tool, an arm arranged to adapt itself to the shape of the inside of the shoe in its different positions and having a flattened upper end positioned substantially in vertical alinement with said tool and con-

- structed to engage the insole of an inverted shoe at the outer edge of the shoe, a standard, and connections between said standard and arm constructed to support said arm 5 for rotation about an axis in substantially vertical alinement with said tool and constructed and arranged normally to position the upper end of said arm in determinate coöperative relation to said gage, including 10 a spring arranged to hold the sole edge of a supported shoe in contact with said gage and arranged to permit said arm to yield to pressure against supported work in a direction laterally of and away from said edge 15 gage.
11. A machine of the class described having, in combination, a tool for operating upon the faces of shoe soles, a work edge gage positioned in determinate relation to 20 said tool, and a work supporting horn formed and arranged to be capable of entering the forepart of a shoe, and rotatably mounted so as to position itself in accordance with the shape and position of the 25 inside of that part of the shoe which from time to time may be brought into coöperative relation to said gage, and positioned in coöperative relation to said gage, and constructed to yield to pressure against supported work in a direction laterally of and 30 away from said gage, and provided with means to control and maintain the direction of lateral movement.
12. A machine of the class described having, in combination, a tool for operating upon the faces of shoe soles, a work edge gage positioned in determinate relation to 35 said tool, and a work support in coöperative relation to said gage constructed and arranged so as to be capable of entering the forepart of a shoe and rotatably mounted to position itself in accordance with the shape and position of the inside of that part of the shoe which from time to time may be 40 brought into coöperative relation to said gage, said work support also being mounted to yield in a determinate direction laterally of and away from said edge gage in response to pressure exerted by said edge gage against 45 a supported shoe.
13. A machine of the class described having, in combination, a tool for operating upon the faces of shoe soles, a work edge gage positioned in determinate relation to 50 the tool, an arm supported for rotation in response to the movement of the shoe thereon by the operative and having a work supporting upper end, a standard, and connections between said standard and arm constructed and arranged normally to position 55 said end of the arm in determinate coöperative relation to said edge gage including spring means to permit said arm to yield to pressure against supported work laterally 60 of and away from said gage, with means determinately to guide said arm in its lateral movement.
14. A machine of the class described having, in combination, a tool for operating upon the faces of shoe soles, a work edge gage positioned in determinate relation to the tool, and an arm supported for rotation in response to the movement of the shoe thereon by the operative and having a work supporting upper end positioned substantially in vertical alinement with said tool and in coöperative relation to said edge gage and supported for rotation about an axis in substantially vertical alinement with said tool, with means arranged to permit movement of said arm through pressure against supported work laterally of and away from said gage, and with guiding means to restrict lateral movement of said arm to a determinate line.
15. A machine of the class described having, in combination, a tool for operating upon the faces of shoe soles, a work edge gage supported in determinate relation to the tool, an arm having a work-engaging end positioned in coöperative relation to said gage and supported for movement relatively to and laterally of said edge gage, means normally tending to move said arm toward said gage, and adjustment means to limit said movement to adjust the normal linear relation of said gage and the work-engaging end of said arm.
16. A machine of the class described having, in combination, a tool for operating upon the faces of shoe soles, a work edge gage supported in determinate relation to the tool, an arm having a work-engaging end positioned in coöperative relation to said gage and supported for movement relatively to and laterally of said gage, spring means normally tending to move said arm toward said gage and arranged to permit movement of said arm laterally away from said gage through pressure against work supported on 100 said arm, and adjustment means to limit spring actuated movement of said arm toward the gage to adjust the normal linear relation of said gage and the work engaging end of the arm.
17. A machine of the class described having, in combination, a tool for operating upon the faces of shoe soles, a work edge gage supported in determinate relation thereto, an arm having a work supporting end positioned substantially in vertical alinement with said tool and in coöperative relation to said gage, and supported for rotation about an axis substantially in vertical alinement with said tool and for lateral movement relatively to said gage, means normally tending to move said arm laterally toward said gage and arranged to permit lateral 110
- 120
- 125

movement of said arm relatively to and away from said gage through pressure against work supported by said arm, and adjustable means to limit such lateral movement toward the gage to vary the normal linear relation of the gage and the work supporting end of the arm.

18. In a machine of the class described, a tool for operating upon the soles of shoes, 5 a gage situated adjacent thereto, a member 10 a gage situated adjacent thereto, a member

extending into the shoe operated upon to furnish a support against the action of the tool and constructed and arranged to rotate in response to the movement of the shoe thereon by the operative, and means for forcing the support yieldingly toward the gage. 15

In testimony whereof I have signed my name to this specification.

CLIFFORD KIRBY MACDONALD.
